CLAIM

The ornamental design for a transport vehicle, as shown and described.

DESCRIPTION

FIG. 1 is an environmental perspective view of a transport vehicle showing my new design, the portion of the figure shown in broken lines representing the environment and forming no part of the claimed design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The second and third baggage compartment doors on the right side of the vehicle are shown in an open position in FIGS. 1, 2, 3, 5 and 6.

FIG. 1

FIG. 4

FIG. 5

FIG. 6
